UNITED STATES PATENT OFFICE

2,592,636

RIVETING GUN AND MAGAZINE THEREFOR

John Aherne-Heron, Farnham Common, Buckinghamshire, England, assignor to Aviation Developments Limited, Welwyn Garden City, Herts, England, a joint-stock company of England

Application February 24, 1948, Serial No. 10,407
In Great Britain January 6, 1939

Section 1, Public Law 690, August 8, 1946
Patent expires January 6, 1959

7 Claims. (Cl. 218—19)

1

The invention relates to riveting guns and like apparatus and to a magazine attachment for feeding rivets thereto.

In the riveting apparatus with which the present invention is concerned, the rivets are tubular and are threaded onto the shank of a mandrel having an enlarged head. The upsetting operation is performed by drawing the head of the mandrel partly or completely through the rivet, from one end of the latter, while a counter-pressure is applied to the opposite end of the rivet by an abutment on the gun.

According to the present invention the riveting gun has a magazine for a number of tubular rivets each mounted on a separate mandrel with an enlarged head, feed means for carrying a rivet and its associated mandrel from the magazine into axial alignment with the gun, means for engaging the mandrel in this position to apply a tractive force thereto and an abutment to provide a counter-pressure while the mandrel head is drawn back to upset the rivet.

The invention also provides a magazine for holding a number of tubular rivets each carried on a mandrel with an enlarged head and having means for presenting a succession of rivets and their associated mandrels for insertion into a riveting gun, the position of the rivets and mandrels when presented for insertion into a riveting gun being preferably determined by a chuck formed of stops releasable when a mandrel is inserted into the gun.

A riveting gun with a magazine in accordance with one form of the invention is illustrated in the accompanying drawings, in which:

Fig. 1 is a view partly in longitudinal section, showing the magazine in position for inserting a fresh mandrel;

Fig. 2 is a view similar to Fig. 1 showing the gun in a position ready for riveting;

Fig. 3 is an axial view of the magazine with an end cover removed;

Fig. 4 is an axial view of the inside of the end cover; and

Fig. 5 is a transverse sectional view through the magazine on the line V—V of Fig. 3.

Referring to Figs. 1 to 4: A riveting gun comprises a casing 100 having within it a carriage 101 which is moved axially by any suitable means to perform the riveting operation. Such means are well known in riveting guns and may comprise a cam. Screwed into the left hand end (as seen in Fig. 1) of the casing 100 is a nose piece 102 into which an anvil 103 is threaded. The tip 104 of the anvil 103 provides an abutment for the head

2

of the rivet during the upsetting operation. The shank of the upsetting mandrel passes through a central passage 105 in the anvil 103, the inner end of said passage being narrowed at 106 to centralise the mandrel.

The end of the shank of the mandrel projects into a recess 107 within the nose piece 102 and is gripped by jaws 108 having conical outer surfaces 109 which coact with corresponding internal surfaces 110 of a sleeve 111 secured by a screw thread 112 to the carriage 101 and axially slideable in guides in the recess 107 in the nose piece 102. The jaws 108 are held together by a wire spring loop 113 and are urged towards the internal surfaces 110 of the sleeve 111 by a light coil spring 114 the other end of which abuts on a plug 115 screwed into the right hand end of the sleeve 111. The plug 115 has a saw cut 116 to facilitate its insertion into or removal from the sleeve 111.

Secured to the casing 100 by bolts 117 is a wedge piece 118 having a guideway 119 which intersects the axis of the riveting gun a short distance in front of the anvil 103.

25 A magazine comprises a casing 120 which serves also as a carriage having flanged edges 121 for cooperation with the guideway 119 to permit movement of the magazine from the position shown in Fig. 1 to that shown in Fig. 2. The casing or carriage 120 has a fixed end cover 122 and a removable flanged cover 123 held in position by a bolt 124 which passes through the centre of the casing or carriage 120 and carries a wing nut 125 locked against a screw nut 126. Within the 30 casing are stored a number of rivets 127 each carried on its associated mandrel 128. The heads 129 at the ends of the mandrels are of greater diameter than the bore of the rivet so that when the mandrel head is drawn into the rivet the 35 shank is upset by outward expansion which forms a bulge at the tail end of the rivet. Hereafter the head of the mandrel may either pass completely through the bore of the rivet or the mandrel may be designed to fracture just below the 40 head when excessive pressure is encountered. This invention is applicable to either type of rivet and mandrel.

The shanks of the mandrels 128 lie in parallel 45 sided radial slots 130 in a cylinder 131 which is mounted on a square part 132 of the shank of the bolt 124 so that rotation of the bolt by means of the wing nut 125 causes turning of the cylinder 131. Each of the slots 130 can accommodate several mandrels along its length. The tail ends 50 of the mandrel shanks 128 pass through a spiral 55

slot 133 in a plate 134 secured within the casing 120, while the shanks of the rivets 127 mounted on said mandrels lie in a similar spiral slot 135 in a plate 136 secured to the inner parts of the flanges of the cover 123 (see Fig. 4). The widths of the slots 133 and 135 are slightly greater than the diameters of the mandrel shank and rivet shank respectively, while the pitch of the convolutions is just greater than the diameter of the head of a rivet. The spiral slot 135 in the plate 136 is continued by a tangential slot 137 of the same width which opens into a space 138 between a pair of spring arms 139 the upper ends of which are adapted to grip the shank of a rivet. The spiral slot 133 is also continued by a short tangential slot.

When the wing nut 125 is turned in the feed direction (clockwise in this case) it turns the cylinder 131 which carries with it the mandrels and rivets lying in its radial slots 130. Owing to the engagement of the tail of the shank and the shank of the rivet in the spiral slots 133 and 135 respectively the rivets move outwardly along these slots as the wing nut 125 is turned, until, upon reaching the periphery of the cylinder at the outer end of the slot, the rivet, with its associated mandrel, is caused to be ejected into the tangential extension 137 of the spiral slot 135. The shank of the mandrel then passes into a tangential slot 140 slightly wider than the diameter of the mandrel shank and which extends to the inclined surface 141 of the casing 120. Upward pressure on the head of its rivet from the head of the rivet below causes the mandrels to move successively up the slot 140 to a position (indicated in Fig. 5) in which the shank of the uppermost rivet is held by the jaws 139. The mandrel tends to pivot, under the upward pressure of the succeeding rivets transmitted through their heads, about the point where it is held by the jaws 139 so that the shank of the mandrel swings upward until it comes into contact with a stop in the form of a spring loaded ball 142 housed in a recess in the wall of the tangential slot 140. In this position the shank of the mandrel is coaxial with the central passage 105 of the anvil 103. It is essential that the mandrel should be located accurately in this position as the feed operation depends on the tail end of the mandrel entering the passage 105.

The feed operation is accomplished by moving the magazine from the position shown in Fig. 1 to that shown in Fig. 2. At the beginning of this movement the tail end of the mandrel shank enters the central passage 105 of the anvil while the head of the mandrel abuts against a plate 143 mounted on the casing 120 of the magazine by wings 144. As the mandrel shank moves down the passage 105, being pressed by the plate 143 as the magazine moves in the direction of the arrow (Fig. 1), the transverse component of the movement of the magazine due to the inclination of the guideway 119 to the axis of the gun causes the rivet and mandrel to be released from the spring arms 139 and spring stop 142. Continued movement of the magazine pushes the mandrel into the gun until its tail end enters between the jaws 138 which grip it lightly under the action of the springs 113 and 114. The plate 143 then moves out of contact with the head of the mandrel and allows the magazine to move into the position ready for riveting as illustrated in Fig. 2.

If at the end of this feed movement the head of the rivet is not in contact with the abutment face 104 of the anvil 103 it is drawn against it

at the commencement of the riveting operation which is effected by drawing the carriage 101 to the right (Fig. 1) relatively to the casing 100 of the gun by means not shown but well known in the art. When the head of the rivet abuts against the face 104 of the anvil 103 the light grip of the jaws 108 on the shank of the mandrel causes relative slip between the inclined surfaces 109 of the jaws 108 and the internal surfaces 110 of the sleeve 111, thereby increasing the gripping pressure of the jaws on the shank of the mandrel to a value preventing slipping between the mandrel and the jaws as the rivet is upset by drawing the head of the mandrel partly or completely through it.

When the upsetting operation has been completed the mandrel is ejected by returning the carriage 101 and jaws 108 to their original position in which the smaller end of the jaws is pressed against the end 145 of the recess 107 causing the jaws to release the shank of the mandrel and allow it to be drawn out again through the central passage 105 of the anvil 103. A fresh rivet and mandrel can then be inserted by again bringing the magazine into the feed position and repeating the operation above described.

If desired the magazine feeding and reciprocating mechanism may be coupled to the operating mechanism of the gun to provide automatic operation.

I claim:

1. A riveting gun having a mandrel-receiving bore extending along the gun axis, said gun being provided with a magazine including a storage member holding in substantially parallel relation and parallel with the gun axis a plurality of tubular rivets each mounted on a separate mandrel with an enlarged head, feed means for carrying a rivet and its associated mandrel in the storage member from a position laterally displaced from the gun axis to a position in axial alignment with said mandrel-receiving bore, means for moving said axially aligned mandrel into said bore through the end thereof, means for engaging the mandrel when positioned within said bore to apply a tractive force thereto and to move the mandrel head axially to upset the rivet, there being an abutment on said gun positioned to provide a counter-pressure upon the rivet while the mandrel head is being moved axially to upset the rivet.

2. A riveting gun according to claim 1 wherein said means for moving the mandrel into the bore comprises guide means supporting said magazine for movement along a guideway extending lengthwise of the gun.

3. A riveting gun according to claim 1 wherein said means for moving the mandrel into the bore comprises guide means forming a guideway for said magazine lengthwise of the gun and angularly disposed with respect to the gun axis.

4. A riveting gun according to claim 1 in which said magazine includes a rotary spindle having storage means mounted thereon in which said rivets and their associated mandrels are stored around said spindle, said storage means including means operative upon turning of said spindle to feed a succession of rivets and mandrels into said axially aligned position for insertion into said gun.

5. A riveting gun according to claim 1 in which said magazine includes a rotary storage member for the rivets and their associated mandrels and has a spirally grooved cam surface to feed the rivets and their associated mandrels successively

into said position of axial alignment with said gun.

6. A riveting gun comprising a round anvil having a central bore for receiving the shank of a rivet-upsetting mandrel, a chuck mounted in the rear of said anvil and having clamping jaws for clamping the end of said mandrel, means mounting said chuck for movement away from said anvil to apply a tractive force to said mandrel, a carriage mounted for reciprocation from a forward position adjacent the front of said anvil to a rear position adjacent the rear of said anvil, and a magazine for upsetting mandrels mounted upon said carriage and being arranged to present a mandrel in axial alignment with the bore of said anvil when said carriage is in its forward position, and being adapted to insert said mandrel into the bore of said anvil upon movement to its rear position.

7. A riveting gun according to claim 6 wherein said carriage moves along an axis disposed at an acute angle with respect to the axis of the gun,

and said magazine is provided with resilient means for releasably holding a mandrel in the feeding position.
